UNITED STATES PATENT OFFICE.

HOUSTON MONROE CARROLL, OF SAN ANTONIO, TEXAS.

WIRE-SCREEN FRAME.

1,250,429.

Specification of Letters Patent. Patented Dec. 18, 1917.

Application filed October 30, 1916. Serial No. 128,569.

To all whom it may concern:

Be it known that I, HOUSTON M. CARROLL, a citizen of the United States, residing at San Antonio, in the county of Bexar and State of Texas, have invented a new and useful Wire-Screen Frame, of which the following is a specification.

The present invention appertains generally to screens, and aims to provide a novel and improved foldable screen adapted to stand across the doorway or other object, and adapted to be hinged to a door, wall or other support, whereby the screen can be folded against said support when not in use and supported in folded position.

Another object of the invention is the provision of a screen frame having novel means for applying and removing the cloth or wire mesh panels, whereby the panels can be removed for cleaning or replacement.

It is also the object of the invention to provide a device of the nature indicated which is simple and inexpensive in construction, and practical and convenient in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is an elevation of the frame as applied to a door to extend across the doorway, one of the panels being removed.

Fig. 2 is a fragmental perspective view illustrating one of the hinge members for hingedly connecting the sections of the frame.

The frame, as illustrated, is composed of three hinged sections, although any suitable number of sections can be used, and each section comprises an upright rectangular auxiliary wire frame having the standards 1 connected at their upper ends by a yoke or cross piece 2. The lower ends of the standards 1 of one section provides feet 3 to rest upon the floor, and said standards are connected adjacent to the feet by a cross piece 4 terminally secured to said standards. Each of the standards 1 of the other frames is provided at its lower end with a cross piece 4'

extending to and secured to the other standard 1, the lower terminal of which provides a foot 3' to rest upon the floor, there being one foot at each end of the main frame and one at the hinges between the sections. The standards 1 of each section are connected between their upper and lower ends by a cross piece 5 terminally secured to said standards.

In order to provide means for supporting the panel, which may be of cloth, wire mesh or other suitable fabric, each frame is provided near its upper and lower ends with relatively short rods 7 secured rigidly to one standard 1, and with opposite relatively long resilient rods 8 secured rigidly to the other standard, said rods 7 and 8 being arranged in pairs, and projecting toward one another, in alinement. Tubular members 9 of shorter length than the rods 8 are provided to fit 75 upon the pairs of rods, and said tubular members are disposed within the upper and lower hems 11 with which the panel 10 is provided. To apply the panel, the tubular members 9 which are within the hems 11 are 80 slipped longitudinally onto the rods 8, which are sprung to one side, and the members 9 can then be slid partially from the rods 8 onto the rods 7, as seen at the lower end of the right hand frame section in Fig. 1. The rods 7 and 8 are thus held in alinement and in rigid position, whereby the panel is held taut between the cross pieces provided by the rods 7 and 8 in connection with the members 9. To remove the panel, it is only necessary to slide the members 9 back onto the rods 8, and then withdraw the members 9 from said rods by springing said rods to one side. This enables the panels to be readily removed for purpose of cleaning or repair, 95 or to enable the panels to be replaced by others.

It is desirable to hinge the outer standards 1 of one end frame to the support, whereby the screen will not be blown over or knocked down accidentally. Thus, said standard can be hinged, as at 12, to a door 13 or other support, and when the screen is not used, the sections thereof can be folded together against the door or support, and the respective standard 1 being slidable vertically as well as rotatable in the bearings 12, enables the folded screen to be raised off of the floor, and the cross pieces or yokes 2 can be engaged over a supporting element 14 110 carried by the door or support to hang the screen up.

The sections of the screen are hinged together by means of S-shaped hinge members 6 pivotally embracing the adjacent standards of the screen sections, reference being had 5 to Fig. 2 to illustrate the hinge member more clearly.

Having thus described the invention, what is claimed as new is:

1. In combination with a door or other support, a screen frame to rest on the floor comprising hingedly connected sections foldable together, means hingedly and slidably connecting one section with the support, and means for hanging the sections of the folded frame, when slid upwardly, from the support.
- 10 2. A screen frame having pairs of members projecting toward one another, members adapted to be slipped onto certain of said members and then slipped partially there-

from onto the other members, and a panel having hems inclosing said members and supported thereby.

3. A screen frame having two pairs of rods projecting toward one another, one rod of each pair being relatively short and the other being relatively long and resilient, tubular members longer than said short rods adapted to be slipped onto the relatively long rods and then slipped partially therefrom onto the relatively short rods, and a panel having hems inclosing said rods and tubular members.

In testimony that I claim the foregoing as my own, I have hereto affixed my signature in the presence of two witnesses.

HOUSTON MONROE CARROLL.
